UNITED STATES PATENT OFFICE

GEORGE PHILIP SCHMITT, OF NEW YORK, N. Y.

DESIGN FOR A FORTUNE-TELLING CARD

Application filed January 29, 1932. Serial No. 42,658. Term of patent 14 years.

To all whom it may concern:

Be it known that I, GEORGE PHILIP SCHMITT, a citizen of the United States, and a resident of the city, county, and State of New York, have invented a new, original, and ornamental Design for Fortune-Telling Card, of which the following is a specification, reference being had to the accompanying drawings forming part thereof.

In the drawings—

Figure 2 is the reverse side of said card.

I claim:

The ornamental design for a fortune-telling card as shown and described.

In testimony whereof I have hereunto set my hand on this 27th day of January, 1932.

GEORGE PHILIP SCHMITT.
